UNITED STATES PATENT OFFICE

CHARLES R. MURRAY, OF CHICAGO, ILLINOIS, ASSIGNOR TO BARNHART BROS. & SPINDLER, OF CHICAGO, ILLINOIS, A CORPORATION OF NEW JERSEY

PRINTING TYPE

Application filed January 16, 1929. Serial No. 332,823.

My invention relates to printing type, and especially to such as are used for what are called "scare heads" in newspapers.

The invention relates to the subject matter of an application of mine filed June 21, 1926, Serial No. 117,261, printing type and system for designating same, and is, to a certain extent, a division and a continuation of said application.

In said application I showed printing type especially intended to be used for headlines, or "scare heads", in newspapers and consequently of large size, and said types are shown arranged in certain sets of series. In the present application I show different letters of the alphabet, whereas in the other application only one letter is shown.

In the accompanying drawings:

Fig. 1 is a view of certain type arranged to illustrate the invention;

Fig. 2 is a view of certain other type for the same purpose;

Figs. 3 and 4 are views of still other type illustrating the invention;

Fig. 5 is a cross section taken on line 5—5 in Fig. 4;

Figs. 6, 7, 8, 9 and 10 are views of type arranged to further illustrate the invention.

Referring to the drawings, Figs. 1 to 5, inclusive, are the figures included in my said other application, Serial No. 117,261. In these figures, Fig. 1 shows five rows of type of one letter; for example, the letter "H". In each of these rows the letters are all of the same height but of different widths. In the successive rows, considered downwardly, the types are successively higher. The corresponding types in the several rows are of the same width.

The types of the first or uppermost row may be considered to be "8 line" types and may be designated by the arbitrary symbol "1". This is indicated at the lefthand side of the first or uppermost row of type in Fig. 1. The width of the type may also be designated by arbitrary symbols, a symbol for each type. For instance, the first or narrowest type may be indicated by "C"; the next by "D"; the next by "E", and so on.

The second row of type may be considered

to be "10 line", which may be indicated by the arbitrary symbol "2", as indicated at the lefthand side of the second row in Fig. 1. The width of these type in the second row, corresponding as it does to the width of the type in the first row, would be indicated by the same arbitrary symbols "C", "D", "E", and so on. Similarly, "12 line" type may be indicated by the arbitrary symbol "3" and the width of different types by the symbols mentioned "15 line" by the arbitrary symbol "4"; "18 line" by the symbol "5", and so on, with widths indicated accordingly.

In Fig. 2 is shown the narrow letters, the "Is" and "Js", which are ordinarily one-half the width or set of the regular type such as the "hs" shown in Fig. 1. In Fig. 3 several "Os" are shown, which are ordinarily one and one-half the regular set or width.

In the type shown in these figures these arbitrary symbols indicating height and width are preferably applied physically to the type themselves. The drawings show, for example, on the first row of "hs", the words "8 line, No. 1", "C", "D" or "E", and so on. Similarly type in second row is marked "10 line, No. 2", "C", "D" or "E", and so on. This marking may be by means of small letters "a" formed on the type themselves in convenient places, preferably between some of the strokes, or portions of the printed face.

In Figs. 6 to 10, inclusive, I show type arranged to indicate the use of the invention in connection with the type arranged alphabetically, and also the use of the invention with reference to the actual physical markings on the type themselves. For instance, in Fig. 6 I show a portion of the alphabet set in type, which may be considered to be "8 line" or "No. 1" type. This may be considered to be width indicated by "C" in Fig. 1 and hence the type of this Fig. 6 would be known as "Series C type, 8 line", or "No. 1".

Fig. 7 shows the same width of type as Fig. 6 and hence the type of this Fig. 7 would also be "Series C". The type of Fig. 7, however, is higher, being "10 line" instead of "8 line" of Fig. 6, and hence this type of Fig. 7 would be "Series C, 10 line", or "No. 2".

Fig. 8 shows type the next size wider than type of Figs. 6 and 7 and this may be designated as "Series D". The type of Fig. 8 is "10 line" or "No. 2". Type of the next size wider than type of Fig. 8 but of the same height would be "Series D, 12 line" or "No. 3". Other series would be indicated as "Series E, 10 line, or No. 2", "Series F, 10 line, or No. 2", and so on; and it may be stated that 10 further series may be used and designated as a continuation of the series, with Figs. 6 and 7 as "Series C, 12 line, No. 3"; "Series C, 15 line, No. 4", and so on.

Fig. 9 shows the next width of type "Series E" of "8 line or No. 1" height. Other "Series E" type would be "10 line No. 2", "12 line No. 3" and so on, of the same width as the type of Fig. 9, but of successively greater height.

20 Similarly, Fig. 10 shows type of "Series F, line No. 1". Other type of this "Series F" would be "10 line No. 2", "12 line No. 3", and so on, for other type of the same width but greater height.

25 In this way type may be readily designated so that it may be handled and selected to great advantage. Type of this kind is usually used for headlines and the head writer's task is simplified and quickened by the fact that 30 he can compute immediately the number of letters to fill a line. Also, he may change type to get headlines of different sized type without rewriting or resetting the copy already prepared for the line, by simply using 35 type of different height of the same series.

Other systems of marking or designation could be used without departing from the invention.

It will be understood that changes and 40 modifications may be made without departing from the spirit of the invention.

What I claim is:

1. A set of type comprising a plurality of 45 fonts or alphabets, whereof like letters have the same width in the several fonts but have different heights in the different fonts.

2. A plurality of sets of type, each set comprising a plurality of fonts or alphabets whereof like letters have the same width but 50 different heights in the fonts of each set but have different widths in the different sets.

3. A plurality of sets of type, each set having like letters of the same width but different heights and the different sets having letters of widths differing from the widths in 55 the other sets but having the same height.

4. Type arranged in different sets whereof type of the different sets have different widths but like type in each set have the same width 60 but different heights, and markings upon said sets of type to indicate the same by arbitrary symbols.

5. A plurality of fonts of type wherein 65 practically all the letters in the several fonts are of the same width but wherein the let-

ters have different heights in different fonts.

6. A plurality of fonts of type wherein like letters in the different fonts have the same width but different heights and wherein also the letters in the different fonts bear 70 the same arbitrary symbol or character to indicate their width irrespective of their height.

7. A plurality of fonts of type wherein the type in different fonts has the same height but different widths and wherein the type in the different fonts is provided with the same arbitrary symbol to indicate height irrespective of width.

In witness whereof, I hereunto subscribe 80 my name this 26th day of September, A. D., 1928.

CHARLES R. MURRAY.
